UNITED STATES PATENT OFFICE.

MAURICE M. GLASSER, OF CHARLESTON, SOUTH CAROLINA.

ELECTRIC FAN.

Application filed November 13, 1924. Serial No. 749,712.

To all whom it may concern:

Be it known that I, MAURICE M. GLASSER, a citizen of the United States, residing at Charleston, in the county of Charleston and 5 State of South Carolina, have invented certain new and useful Improvements in Electric Fans; and I do hereby declare the following to be a full, clear, and exact description of the same, reference being had to the 10 accompanying drawings, forming part of this specification.

This invention relates to an oscillating electric fan and particularly to improvements in a fan of the general type shown in 15 my prior Patent No. 1,354,098, dated September 20, 1920, on an oscillator for electric fans.

In fans of this type the rotor, journaled in a yoke, is adapted to be oscillated about 20 the axis of its journal, while separate mechanism is provided for rotating the yoke and fan about an axis at right angles to the axis of oscillation of the rotor whereby the blasts of air created by the oscillating rotor will 25 constantly sweep in a new plane. This insures the blasts of air reaching all points around the room and makes the fan especially adapted for use in cases where it is preferred not to have the fan continuously 30 throwing the air in fixed or limited directions.

Usually this rotation of the rotor and yoke is accomplished intermittently but in some cases it has been found that the means for 35 accomplishing this intermittent movement ceases to function, and the primary object of the present invention is to provide means for causing this rotation of the rotor in a way that will be sure in operation.

40 In carrying out this primary object the invention also contemplates the form of mechanism that will be simple in its operation, not apt to get out of working order, and which will have a comparatively low 45 production cost.

With these and other objects in view the invention consists in certain novel details of construction and combinations, and arrangements of parts all as will be herein- 50 after more fully described and the novel

features thereof particularly pointed out in the appended claims.

In the accompanying drawings,

Figure 1 is a side elevation of a fan embodying the present improvements. 55

Fig. 2 is a vertical sectional view of the structure by which the rotor carrying yoke is supported from the ceiling or other surface.

Fig. 3 is a more or less detail view showing the mechanism for causing the rotation of the yoke by the oscillating motor casing. 60

Fig. 4 is a horizontal sectional view taken on the line 4—4 of Fig. 2.

Fig. 5 is a similar view taken on the line 65 5—5 of Fig. 2; and

Fig. 6 is a view taken on the line 6—6 of Fig. 2.

In the preferred construction the motor supporting yoke 10 is rotatably supported 70 on a shaft 11 which is provided at one end with a screw threaded socket 12 for attachment to a suitable fixture 13 that is secured to the ceiling or other supporting surface. The motor casing 14 carrying the motor, 75 and the fan blades 15 on the motor shaft, is journaled at the depending ends of the yoke arms and is adapted to be oscillated on its bearings by the crank disk 16 operated by suitable gearing within the motor (not 80 shown), said crank disk having a connecting rod 17 extending between it and a fixed plate 18 so that the rotation of the disk will cause the motor casing to be oscillated back and forth. 85

The yoke 10 is provided with a sleeve 19 taking a bearing on the shaft 11 and surrounding said sleeve is another sleeve 20 of any suitable insulating material, this latter sleeve being provided at its lower end with a disk of insulating material 21 resting on the top of the yoke 10. Surrounding sleeve 20 is a second sleeve 22 of insulating material around which there is secured preferably three current collecting rings 23, 24, 90 25, from which three current conducting strips such as shown at 26 extend down between sleeves 20, 21, to suitable terminals 27 secured on a disk of insulating material 28 which is clamped or secured to the yoke 95 100

10 by a bolt 29 passing through said disk 28 and through disk 21 into the yoke. Each of these rings 23, 24, 25, is adapted to be engaged by a circular strip 30 of conducting material, preferably copper or brass whose end portions 30 substantially entirely encircle its rings and whose intermediate portion extends through an opening in the cap or housing 32 and is bent upon itself to form 15 a recess 31 in which there is a piece of lubricant saturated material 70, such as felt, which aids in lubricating the contacting surfaces of the collecting rings and strips 30. One of the bent back portions 33 of each 20 split ring 30 is engaged by a spring 34, the pressure of which on the strip is regulated by a screw 35 in the cap 32, so that the pressure of the conducting ring on the collecting ring can be varied by adjustment of said 25 screw. The housing 32 and the cylindrical shell 36 which encircles the parts just described are secured by screws 37 to a flange 38 formed on the shaft 11 immediately below the screw threaded socket 12, this shell 36 extends down around all the parts just 30 described and covers the same to hide and protect the electrical engagement between the collecting rings and the conducting ring. Current is brought by wires 39 to one end 35 of the conducting rings 30 and may be carried from the terminals or binding posts 27 to the motor by wire arranged in any desired way.

The mechanism for intermittently rotating the yoke on the shaft 11 to cause the successive oscillations of the fan blades to take place in successively different planes is carried at the lower end of said shaft 11. This mechanism preferably comprises a latch lever having a down-turned end 50 and a curved end portion 51 loosely secured between the flanges 52, 53 of a sleeve secured rigid to the lower end of shaft 11 by a disk and lag screw 54. The curved portion 45 of the latch lever is free to rotate on the sleeve when moved in one direction by the oscillation of the motor casing but when moved in the opposite direction by the motor casing said curved end portion 51 is adapted 50 to be locked to the sleeve whereby the yoke will be caused to turn on the shaft 11. To accomplish this co-operating locking elements are provided on said curved end portion 51 of the latch and the flange 52 of said 55 sleeve.

Said locking elements preferably consist of a series of apertures 55 in said flange and a projection, such as a screw 56 secured in the curved end portion of the latch lever. 60 To permit the curved end portion 51 of the latch lever to move freely in one direction but to cause the screw to engage one of the apertures in the flange 52 there is provided a split ring member 60 surrounding the 65 sleeve which is provided with projections

58 against which the curved portion 51 abuts at times. Said ring member is free to rotate on the sleeve so that when the motor casing 14 is oscillated as shown in Fig. 3 and the finger 59 engages arm 50 of the latch lever to move it toward the left, the end of the curved portion 51 will move into contact with projection 58 and the ring member 60 and curved portion 51 will both move or 70 rotate on the sleeve. 75

The frictional engagement between said ring and sleeve, however, is such that when the direction of oscillation of the motor casing is reversed and the finger 61 comes against arm 50 and portion 51 engages the projecting end of the ring, the curved end portion of the latch lever carrying the projection 56 will be tilted or lifted up. The frictional contact of the ring and sleeve, however, permits the ring to move until projection 56 comes into registry with and engages in one of the apertures in the flange 52. The parts will then be locked together and sleeve 54 being fixed on the shaft, the arm 50 cannot move toward the right, in Fig. 3, with the result that the yoke 10 will rotate a short distance on shaft 11. After the fan has reached the limit of its oscillation and again reverses its direction of movement, curved end portion 51 of the latch lever will move or drop down, as shown in Fig. 3, to disengage the projection 56, and when finger 59 again comes in contact with arm 50, curved end portion 51 and the ring member 60 will be free to rotate on the sleeve, as before described. 100

To regulate the frictional engagement between ring 60 and the sleeve and to provide projections on the ring against which the latch lever will engage, said ring is preferably made in the form of a split ring with its end portions extending around the sleeve and its intermediate portion bent back upon itself to form the projection 58 which extends out beyond the edges of flanges 52 and 53. Said intermediate portions are connected together by a screw 62 to hold the ring in proper frictional engagement with the sleeve. By moving the tap on the screw 62 the frictional engagement between the parts can be regulated at will. To take some of the strain off of the yoke and the parts secured to the shaft end by lag screw 54, a spring washer 64 is interposed between the top of flange 52 and yoke 10. 110

In order that lubricant will be conveyed to the various relatively moving parts the shaft 11 is provided with lubricant recesses 66, lubricant being supplied between the shaft 11 and sleeve 19 through a duct 65 formed at the point where the upper surface of the flange 38 merges with the socketed upper end 12 of the shaft. The lubricant deposited in the duct will work itself around to all portions of the contacting sur- 115 120 125 130

faces of shaft 11 and sleeve 19, as will be readily understood. Lubricant for the contacting surfaces of collecting rings 23 to 25 and conducting rings 30 is taken care of by the provision of circumferentially extending grooves 67 in the exterior surfaces of the collecting rings in which lubricant can be deposited before the parts are assembled.

- 10 To properly lubricate the exterior of sleeve said sleeve is provided with one or more reservoirs such as wicks 68 secured in the sleeve and adapted to be saturated with suitable lubricant which can reach the exterior surface of the sleeve through a circumferential groove 69 in the exterior of said sleeve, the recess being of sufficient depth as to intersect the holes in which the wicks are secured.
- 15 20 With a yoke rotating mechanism, such as described, the cost of production is greatly reduced and while the parts are comparatively simple they are exceedingly efficient in that there is little likelihood of their failing to function. The frictional engagement between ring 60 and the sleeve being easily regulated, the curved end portion of the latch lever is sure to be raised each time the motor casing oscillates towards the right, as shown in Fig. 3, and said curved end portion being loose on the sleeve, the latch lever is sure to free projection 56 from the flange 52 after the motor casing has reached its limit of movement when oscillating toward the right, when looking at Fig. 3.

What I claim is:

1. In an electric fan, a supporting element, a yoke rotatable on said member, a motor casing journaled in the yoke, means for oscillating the casing in a plane at right angles to the direction of rotation of the yoke, and means for intermittently rotating the yoke, said means comprising a plate fixed to the supporting element, a latch lever, cooperating latching elements on said plate and lever normally held disengaged by gravity, and means controlled by the oscillation of the motor casing for positively moving said latching elements into engagement.
2. In an electric fan, a supporting element, a yoke rotatable on said element, a motor casing journaled on the arms of the yoke, means for oscillating said casing in a plane at right angles to the direction of rotation of the yoke, and means for intermittently rotating said yoke, said means comprising a fixed member, a latch member, cooperating latching elements, means carried by the casing for rotating the latch member with the latching elements held disengaged by gravity during oscillation of the casing in one direction and means for positively moving the latching members into engagement upon oscillation of the casing in the opposite direction.

3. In an electric fan, a supporting element, a yoke rotatable on said element, a motor casing journaled on the arms of the yoke, means for oscillating said casing in a plane at right angles to the direction of rotation of the yoke, and means for intermittently rotating said yoke, said means comprising a fixed plate having a series of apertures therein, a latch member having a circular portion surrounding the supporting element and a depending arm, there being a projection on said circular portion normally held by gravity out of engagement with the apertures in the plate, spaced fingers carried by the casing adapted to oscillate the arm of the latch member and rotate the circular portion of said member, said circular portion being free to rotate on the supporting member in one direction while the projection is disengaged from said apertures, and means for positively elevating said circular portion of the latch member when the casing tends to oscillate said member in the opposite direction whereby the projection on the circular portion is moved into one of said apertures.

4. In an electric fan, a supporting element, a yoke rotatable on said element, a motor casing journaled on the arms of the yoke, means for oscillating said casing in a plane at right angles to the direction of rotation of the yoke, and means for intermittently rotating said yoke, said means comprising a sleeve fixed on the supporting element and having an apertured flange, a split ring member surrounding said sleeve and rotatable thereon, a latch lever having a circular portion surrounding said sleeve and a depending arm, a projection on said circular portion, means carried by the casing adapted to oscillate said arm whereby the circular portion is alternately moved in opposite directions, and means on said ring member for limiting the movement of said circular portion of the latch lever in one direction and positively moving the projection on the latch lever into engagement with an aperture in the flange of the fixed sleeve.

5. In an electric fan, a supporting element, a yoke rotatable on said element, a motor casing journaled on the arms of the yoke, means for oscillating said casing in a plane at right angles to the direction of rotation of the yoke, and means for intermittently rotating said yoke, said means comprising a sleeve fixed on the supporting element, a split ring surrounding and frictionally engaging said sleeve, a latch member surrounding said sleeve, a flange on the sleeve, cooperating latching elements carried by said latch member and flange, said latching elements being normally held disengaged by gravity, means on the casing for rotating the latch member alternately in opposite direction, the frictional engagement

between said ring and sleeve being such that said latch member is free to rotate on the sleeve in one direction, and means on said ring engageable by the latch member when moved in the opposite direction to move the cooperating latching elements into engagement with each other.

6. In an electric fan, a supporting element, a yoke rotatable on said element, a motor casing journaled on the yoke, means for oscillating the casing in a plane at right angles to the direction of rotation of the yoke, and means for intermittently rotating the yoke, said means comprising a sleeve on said supporting element, a latch lever surrounding said sleeve, cooperating latching elements carried by the sleeve and latch lever, means on the motor casing for alternately rotating said latch lever in opposite directions, means surrounding said sleeve and engaging said latch lever, said means being freely movable with said lever in one direction and frictionally held against movement in the opposite direction to move said cooperating latching elements into engagement with each other.

7. In an electric fan, a supporting element, a yoke rotatable on said element, a motor casing journaled on the yoke, means for oscillating the casing in a plane at right angles to the direction of rotation of the yoke, and means for intermittently rotating the yoke, said means comprising a sleeve on said supporting element, a latch lever surrounding said sleeve, cooperating latching elements carried by the sleeve and latch lever, means on the motor casing for alternately rotating said latch lever in opposite directions, a split ring surrounding said sleeve and engaging said latch lever, said split ring being freely movable with said lever in one direction and frictionally held against movement in the opposite direction to move said cooperating latching elements into engagement with each other, and means for regulating the frictional engagement between said split ring and sleeve.

8. In an electric fan, a supporting element, a yoke rotatable on said element, a motor casing journaled on the yoke, means for oscillating the casing in a plane at right angles to the direction of rotation of the yoke, and means for intermittently rotating the yoke, said means comprising a sleeve on said supporting element, a latch lever surrounding said sleeve, cooperating latching elements carried by the sleeve and latch lever, means on the motor casing for alternately rotating said latch lever in opposite directions, a split ring surrounding said sleeve and engaging said latch lever, said split ring being freely movable with said lever in one direction and frictionally held against movement in the opposite direction to move said cooperating latching elements

into engagement with each other, means for regulating the frictional engagement between said split ring and sleeve, and an oil reservoir in said sleeve, there being a recess in the exterior of said sleeve communicating with said reservoir whereby lubricant will be delivered to the surface of the sleeve on which said split ring and latch lever rotate.

9. In an electric fan, a supporting element, a fixed sleeve surrounding the support, a latch member having a curved end portion loose on the sleeve and a depending arm, a yoke rotatable on the support, a motor casing journaled on the yoke, means for oscillating the casing in a plane at right angles to the direction of rotation of the yoke, means on the casing engaging the latch arm to rotate the curved end portion of said latch alternately in opposite directions, and means permitting rotation of said curved end portion in one direction about the sleeve while locking said curved end portion to the sleeve when rotated in the opposite direction.

10. In an electric fan, a supporting element, a fixed sleeve on the support, a latch member having an end curved portion loose on the sleeve, cooperating latching elements carried by said sleeve and the curved portion of the latch, a yoke rotatable on the support, a motor casing journaled in the yoke, means for oscillating the casing, means for rotating the curved portion of the latch alternately in opposite directions, and means for limiting the movement of the curved portion in one direction and moving said cooperating latching elements into engagement.

11. In an electric fan, a supporting element, a fixed sleeve on the support, a latch member having an end curved portion loose on the sleeve, cooperating latching elements carried by said sleeve and the curved portion of the latch, a yoke rotatable on the support, a motor casing journaled in the yoke, means for oscillating the casing, means for rotating the curved portion of the latch alternately in opposite directions, and a ring surrounding said sleeve and provided with a projection adapted to engage the curved portion of the latch when the latter is rotated in either direction, said ring being free to rotate on the sleeve in one direction but held against movement in the opposite direction to effect engagement of the said cooperating latching elements.

12. In an electric fan, a supporting element, a fixed sleeve on the support, a latch member having an end curved portion loose on the sleeve, cooperating latching elements carried by said sleeve and the curved portion of the latch, a yoke rotatable on the support, a motor casing journaled in the yoke, means for oscillating the casing, means for

rotating the curved portion of the latch alternately in opposite directions, a split ring surrounding said sleeve and provided with a projection adapted to engage the curved portion of the latch when the latter is rotated in either direction, said ring being free to rotate on the sleeve in one direction but frictionally held against movement in the opposite direction to effect engagement of said cooperating latching elements, and means for regulating the frictional engagement between said ring and sleeve.

MAURICE M. GLASSER.
